Patented Aug. 3, 1926.

UNITED STATES PATENT OFFICE.

ROOD P. STEELE AND JOHN DWYER, OF FRANKLIN, PENNSYLVANIA, ASSIGNEES TO
S. G. MILTON & SON, OF FRANKLIN, PENNSYLVANIA, A COPARTNERSHIP.

PULLING MACHINE.

Application filed August 13, 1925. Serial No. 50,042.

Our invention relates to apparatus which is especially adapted for use in pulling the pump rods, tubing, etc., of oil wells and the like, although it may, of course, be put 5 to other uses.

Patent No. 963,237 of July 5, 1910, to S. G. Milton, shows a type of pulling apparatus to which our invention is particularly applicable.

10 Our invention resides more particularly in the provision of means whereby a tractor provided with a winch or winding drum may be conveniently and effectively employed in connection with the mast of a 15 pulling apparatus, and has for one of its objects the provision of means whereby the pulling mast structure and the tractor may be braced, one by the other, during a pulling operation and wherein a workman may 20 not be injured by coming between the tractor and the mast as sometimes happens in present practice.

One form which our invention may take 25 is shown in the accompanying drawing wherein Fig. 1 is a view, in side elevation, of apparatus embodying our invention; Fig. 2 is a rear elevational view of a portion of the apparatus of Fig. 1, and Fig. 3 is a view, on an enlarged scale, of an at- 30 taching bracket by means of which the apparatus may be connected to the pulling mast structure.

In the course of development of the art, 35 tractors were substituted for horses in pulling tubes and pump rods of oil wells, masts similar to that shown in the drawing being employed and provided with guiding sheaves or pulleys around which a cable was passed, one end of the cable being 40 hitched to the rod or tube being pulled, and the other end to harness traces. The trac- 45 tors usually come equipped with a winch or winding drum and have commonly been anchored to a tree or a stake. The pulling 50 rope or cable that extends over the mast pulley is wound on the winch. Frequently the tractor breaks loose from its anchorage and may hit the mast with such force as to 55 break the same. Furthermore, workmen have been sometimes injured through being present between the tractor and the mast at times when the tractor breaks loose.

In the accompanying drawing we have 55 shown a tractor 4 which is provided with a power shaft that may be of the usual form

found on many tractors and may be mounted at either the rear end or the front of the tractor. The shaft 5 is provided with a pinion 6 that meshes with a gear wheel 7 of a winding drum or winch. The gear 60 wheel 7 is mounted in bearings that are supported from the tractor 4 by means of brackets 8.

The mast is shown as having a framework composed of horizontal channel irons 65 9 and vertical channels 10, for supporting the mast sections 11 and 12. The shaft is provided with a sheave 13 over which passes a rope or cable 14. One end of the cable is connected to the tubing or pump rods of 70 a well 15 when it is desired to pull the same, and the other end is connected to the winding drum or winch above referred to.

To each of the channel members 10 we bolt a bracket member 16. A brace member 75 17 is bolted at its upper end to the bracket 16 and at its lower end to the mast frame.

During the operation of the device, the tractor is positioned against the bracket members 16 so that both the tractor and the 80 mast will be braced, by reason of their abutting engagement with one another, against movement. It is desirable, however, that means be provided for preventing displacement of the tractor and the mast frame and for this purpose we employ, at each side of the tractor, a metal bar or strap 18 whose lower end is provided with a hole through which a bolt 19 may extend, for the purpose of securing said bar to the tractor. The bolt 19 may replace the usual 90 shorter bolt by which the bearing for the gear wheel 7 is secured to the tractor frame. Washers or spacers 20 may be conveniently employed, although the lower end of the bar 18 may be so bent as to render such spacers unnecessary.

The upper ends of the bars 18 are provided with either a slot 21 as shown, or with a plurality of holes, by means of which they may be adjustably secured to the brackets 16. Bolts 22 extend through the brackets 16 and the slots 21. This arrangement permits the tractor to be readily secured to the mast even though the tractor and the mast frame are not in perfect alignment, as when the surface of the ground is uneven.

It will be seen that the tractor and the mast require no other means for holding them against relative movement in a hori- 110

zontal direction, and that it is impossible for a workman to walk between them.

We claim as our invention:—

1. The combination with a mast structure provided with frame members extending in a vertical direction at its sides, and a tractor provided with a horizontally disposed winch shaft, of means for connecting said winch member at each of its ends to said side frame members, comprising a bar secured to said winch at each end thereof and to one of said side frame members.

2. The combination with a mast structure adapted for use in pulling tubing and the like, and a tractor provided with a winch-supporting frame, of a bracket connected to said mast, and means for connecting said winch frame to said bracket, comprising a bar secured to said frame at each end thereof and a vertically adjustable connection between one of said bars and said bracket.

3. The combination with a mast structure

adapted for handling tubing and the like, and a tractor provided with a winch having an axle disposed in a horizontal plane, of a bearing adjacent to each end of said axle, and laterally spaced bracket members connected to said mast structure and each having engagement with one of said bearings.

4. The combination with a mast structure adapted for handling tubing and the like, and a tractor provided with a winch having an axle disposed in a horizontal plane, of a bearing adjacent to each end of said axle, and laterally spaced bracket members connected to said mast structure and each having adjustable connection with one of said bearings.

In testimony whereof we, the said ROOD P. STEELE and JOHN DWYER have hereunto set our hands.

ROOD P. STEELE.
JOHN DWYER.
